JAMES J. HOGAN, JOHN F. JUDD, AND LYMAN M. WAITE, OF FITCHBURG, MASSACHUSETTS, ASSIGNEES TO FITCHBURG MACHINE WORKS, OF FITCHBURG, MASSACHUSETTS, A CORPORATION OF MASSACHUSETTS.

THREADING MECHANISM FOR AUTOMATIC LATHES.

1,222,954.

Specification of Letters Patent. Patented Apr. 17, 1917.

Application filed May 19, 1916. Serial No. 98,659.

To all whom it may concern:

Be it known that we, JAMES J. HOGAN, JOHN F. JUDD, and LYMAN M. WAITE, citizens of the United States, all residing at 5 Fitchburg, in the county of Worcester and State of Massachusetts, have invented a new and useful Threading Mechanism for Automatic Lathes, of which the following is a specification.

10 This invention relates to a threading mechanism for automatic lathes of the type in which the threading die is continuously revolved in the same direction as the stock, but at a speed less or greater than that of the stock according as the die is cutting or running off of the stock.

While many features of our invention are capable of general application, we have herein shown the invention as applied to a multiple spindle automatic lathe of the general type shown in the patent to Grant, No. 926,735, issued July 6, 1909. In this type of lathe the work is both rotated and advanced longitudinally toward the tools which are 25 mounted in a fixed tool head.

It is the general object of our invention to provide an improved threading mechanism particularly adapted to this type of lathe, in which the mechanical construction 30 is simplified and the operation is made more reliable.

With this general object in view, one feature of our invention relates to a construction by the use of which the threading mechanism may occupy either one of two successive positions in the lathe, or if desired two threading mechanisms may be used at the same time, one in each of two successive 35 positions. A second feature of our invention relates to the provision of a support on which is mounted the mechanism which controls the threading die, this support and the mechanism thereon being readily removable and replaceable as a unit. Other features of our invention relate to the provision 40 of an improved system of controlling devices for the threading mechanism by which the necessary adjustments can be easily made and to an improved and simplified 45 clutch mechanism for controlling the speed changes of the die.

Our invention also relates to certain arrangements and combinations of parts which will be hereinafter described and more particularly pointed out in the appended claims.

A preferred form of our invention is shown in the drawings in which—

Figure 1 is a side elevation of a portion of a lathe, with our improved threading mechanism attached thereto;

Fig. 2 is a top plan view of the mechanism shown in Fig. 1;

Fig. 3 is a left-hand end elevation, partly in section taken along the line 3—3 in Fig. 1;

Fig. 4 is a front elevation of the die spindle and associated parts, partly in section, and taken along the line 4—4 in Fig. 2;

Fig. 5 is a front elevation of the detachable support for the die controlling mechanism, and the parts carried thereby;

Fig. 6 is a detail elevation of the compound lever through which the speed changes of the threading die are controlled, taken along the line 6—6 in Fig. 1;

Fig. 7 is a front elevation of the compound lever shown in Fig. 6;

Fig. 8 is a sectional view taken along the line 8—8 in Fig. 4, and showing the clutch mechanism for the low speed drive;

Fig. 9 is a partial sectional view similar 80 to Fig. 8, but showing the parts in a different position;

Fig. 10 is a sectional view taken along the line 10—10 in Fig. 4, and showing the clutch mechanism for the high speed 85 drive;

Fig. 11 is a partial sectional view similar to Fig. 10, but showing the parts in a different position, and

Fig. 12 is a detail sectional view taken 90 along the line 12—12 in Fig. 4.

Referring to the drawings we have indicated at 10—10 two of the rotatable spindles which support consecutive pieces of work W. These spindles are mounted in 95 a head 11 slidable on ways 12 formed on the bed 13 of the machine. The movement of the head is controlled through connections, not shown, from a main cam shaft 14 rotatable in suitable bearings in the bed 13. 100 The usual box tools are mounted in a rigid tool head 15, and the threading die 16 is secured to a spindle 17 (Fig. 4), rotatable and slidable in the tool head 15.

At the left of the tool head 15 there is 105 provided an additional fixed frame member 18 having guide ways 19 and 20 (Fig. 3) formed on the front face thereof. A support 21 (Figs. 3 and 5) is provided with a dovetailed groove by means of which the 110

support may be accurately positioned upon either guide way to correspond to the third or fourth positions of the work holding spindles.

- 5 As shown in the drawings the support is mounted on the upper guide way or in the third position, but it may be readily removed therefrom and may be replaced in the fourth position upon the guide way 20. Furthermore it is sometimes desirable to perform two successive threading operations in an automatic lathe, and for such purposes a separate support 21 with its attached mechanism may be mounted upon each of the 10 guide ways 19 and 20, thus permitting the threading operations to be performed in both the third and fourth positions.
- The mechanism mounted upon the support 21 is used for advancing and withdrawing 20 the die relatively to the work, and also for controlling the speed changes of the die. For the purpose of positioning the die axially a rack sleeve 22 (Fig. 5) is slidably but non-rotatably mounted in a bearing 21^a on 25 the support 21. An intermediate shaft 23 is rotatable in a bearing 21^b on the support 21 and a rod 230 fixed in said shaft extends freely through the sleeve 22 and is retained therein by a collar 231.

- 30 A swivel connection is thus formed between the shaft 23 and the sleeve 22. The shaft 23 extends into a recess 170 (Fig. 4) formed in the end of the spindle 17, and is retained therein by a cross pin 232 which 35 extends through slots 233 in the spindle 17. A spring 234 in the recess 170 holds the pin normally against the outer ends of the slots but permits the parts to yield when the threading die engages the work.
- 40 The rack teeth upon the sleeve 22 are positioned to engage a spur gear 24 mounted on a short shaft 25, rotatable in bearings in the support 21. A pinion 26 is secured to the outer end of the shaft 25 and meshes with a 45 segment gear 27 pivoted upon a stud 28 secured to the support 21. The support 21 is fixed upon the frame member 18 by a number of bolts or studs 29 (Fig. 2).

A roll 30 (Figs. 2 and 5) is mounted in 50 an arm 31 which is adjustable about the axis of the stud 28, and which may be fixed to the segment gear 27 by means of a bolt 32 extending through a segmental slot 33 formed in the gear. The roll 30 is positioned for 55 engagement by a pawl or dog 34 (Fig. 2) pivoted in a block 35, keyed to a sliding bar 36, and longitudinally adjustable thereon.

The bar 36 carries a series of pawls or dogs for controlling the operations of the 60 threading die when in the upper or third position, and a corresponding bar 37 is provided for supporting the dogs which control the threading mechanism when in the fourth position. The bars 36 and 37 are slidable at

their right-hand ends in bearings 38—38⁶⁵ (Fig. 1) formed on the side of the tool head 15. The bars also extend through a cross bar 39 to which each bar is rigidly secured. A third bar 40 is secured at one end to the center of the cross bar 39 and is slidable in a bearing 41 carried by the frame member 18. The bars 36 and 37 are thus supported for longitudinal reciprocation parallel to the axis of the threading die and the work holding spindles.

The cross bar 39 is connected by a link 42 to the upper end of an arm 43 keyed to a horizontal shaft 44 which is mounted in fixed bearings in the frame 13. A second arm 45 is secured to the shaft 44 between 80 the sides of the frame and is provided with a cam roll 46 positioned to engage an irregular cam 47 mounted upon the main or cam shaft 14. This shaft 14 makes one complete revolution for each advance of the work-holding spindles, and the sliding bars 36 and 37 are therefore given one full reciprocation after each advance of the spindles to new positions.

As the bar 36 is moved to the right after 90 the work W is positioned in front of the threading die 16, the pawl or dog 34 engages the roll 30 and partially rotates the segment gear 27, thereby advancing the rack sleeve 22, the shaft 23, the spindle 17 and the die 95 16. By the continued movement of the segment gear 27 the roll 30 is carried downward until the dog 34 passes freely over the roll.

The parts are so timed that the advancing stock W will engage the die substantially at 100 the moment when the roll 30 passes below the dog 34. At this instant the dog, being directly above the roll, is effective to prevent backward movement of the die, thus holding the die against the thrust of the work until 105 the die begins to feed forward in its cutting movement, when the shaft 23 and sleeve 22 will be drawn forward by the die independently of the dog 34.

We will now describe the mechanism for 110 rotating the die at suitable speeds to secure the cutting of the thread and the withdrawal of the die. A sleeve 50 (Fig. 4) is loosely mounted upon the intermediate shaft 23, but is prevented from free rotation thereon by a loose key or tumbler 51 (Fig. 8) which closely limits the relative angular movement of the sleeve and shaft. The tumbler 51 is held within the sleeve 50 by a cap 50^a (Fig. 4) which is extended to find a bearing 115 120 in the head 15.

A high speed gear 52 normally rotates freely upon the outside of the sleeve 50, and a low speed gear 53 is also mounted for rotation concentric with the shaft 23 and sleeve 50. The gears 52 and 53 are constantly driven by gears 54 and 55 (Fig. 2) suitably connected with the driving mechanism of the 125

machine, the proportions of the gears being such that the gear 52 will rotate at a speed greater than that of the work, while the gear 53 rotates at a speed less than that of the work.

The operation of these gears during thread cutting is such that the gear 53 acts as a brake or retarding device to hold the die back so that the work will be turned into the die during the cutting operation, while the gear 52 drives the die ahead of the work, so that the die will be run off after the thread has been cut.

Under normal conditions the shaft 23 and the threading die are continuously rotated at slow speed by the gear 53. This gear is provided upon its inner surface with a series of ratchet teeth 56 (Fig. 8) positioned for engagement with a pawl 57 slidable outwardly in a recess in the sleeve 50. A light flat spring 58 forces the pawl yieldingly outwardly to engage the ratchet teeth 56 and this spring is of sufficient strength to maintain the driving engagement between the gear 53 and the shaft 23 when no thread is being cut.

As soon as the die engages the stock it tends to rotate at the same speed as the stock, and therefore to run ahead of the gear 53 and the sleeve 50 which is latched thereto by the pawl 57. Under these conditions the shaft 23 presses against the lower end of the tumbler 51 (as viewed in Fig. 8). The tumbler, however, engages the sleeve 50 only at a point near the center of the tumbler, and the pressure of the shaft 23 therefore acts through the tumbler 51 as a lever to positively hold the pawl 57 in engagement with the ratchet teeth 56. So long as the die is cutting, therefore, the gear 53 retards the rotation of the die, and the pull of the stock transmitted through the shaft 23 and the tumbler 51 holds the pawl 57 in operative engagement with the teeth 56.

After the thread has been cut to the desired length it is necessary to connect the high speed gear 52 to the shaft 23 in order that the die may be run off of the work. The gear 52 is provided with oppositely disposed ratchet teeth 60 (Fig. 10) and a sliding pawl 61 is mounted in a recess in the sleeve 50. A collar 62 (Fig. 4) is slidable upon the shaft 23, said collar being formed of two diameters. When the pawl 61 engages the smaller diameter, as shown in Figs. 4 and 10, the high speed gear is inoperative. When the collar is moved to the right so that its portion of larger diameter engages the pawl, the pawl is moved outwardly to the position shown in Fig. 11 and thus connects the high speed gear to drive the sleeve 50.

The sleeve 62 is slidably secured to the shaft 23 by a key pin 64 (Fig. 12) which engages a key way or slot 65 formed in the

shaft 23. At its left hand end the sleeve 62 is provided with a flange 62^a fitting loosely within a pocket in a two part sleeve 66 slidable in a bearing formed on the support 21. A stud 67 (Fig. 3) carried by the sleeve 66 extends through a slot in the side of the bearing into position for engagement by a compound operating lever.

The compound lever comprises a member 70 (Fig. 7) pivoted at 71 to the support 21, 75 and having a slotted engagement at its lower end with the stud 67. At its upper end the member 70 is provided with a stud 72 which extends through a slot 73 in the second member 74 of the compound lever. The 80 member 74 is made in two parts for purpose of adjustment and is pivoted at 75 to the support 21. This member has an engaging portion 74^a which extends downwardly into the path of a dog 76 pivoted 85 in a block 77, and adjustably secured to the sliding bar 36.

We have previously described the manner in which the die is advanced by the dog 34 until it engages the stock. It is then drawn 90 forward upon the stock during the cutting operation, and at the same time the stock is advancing toward the left as viewed in the drawings. The dog 76 will be so adjusted that it will engage the portion 74^a of the 95 compound lever when substantially the desired length of thread has been cut. Such engagement through the stud 67 and the sleeve 66 will slide the sleeve 62 to the right along the shaft 23, thus forcing outward 100 the pawl 61 and causing driving engagement of the high speed gear 52. The die will then be rotated faster than the work W with the result that it will be quickly run off of the work.

During this portion of the operation the sleeve 50 will drive the shaft 23 instead of retarding the same, and the tumbler 51 will be moved to the position shown in Fig. 9, thus releasing the pawl 57 which will thereafter snap lightly over the ratchet teeth 56, being forced outward only by the light spring 58.

After the die has been withdrawn from the work, a third dog 80 (Fig. 2) pivoted in a block 81 adjustable on the bar 36 engages a shoulder 27^a (Fig. 5) of the segment gear 27 and partially rotates the gear in a direction opposite to that caused by the engagement of the pawl 34 with the roll 30. The 115 sleeve 22 and shaft 23, and the spindle 17 are thus positively returned to their original inoperative positions.

As the shaft 23 approaches its extreme left-hand position the key pin 64 (Figs. 4 and 12) reaches the end of the slot 65, and is thereafter moved a short distance to the left carrying with it the sleeve 62, and releasing the pawl 61, thereby disengaging the high speed gear 52, and restoring the 120 125 130

spindle 23 to the control of the low speed gear 53.

It will be noted that the entire operation thus far described has taken place during the continued movement of the bar 36 to the right. After these operations have been completed the bar 36 makes an idle stroke to the left in returning to initial position. The dogs 34, 76 and 80 are each yieldingly mounted in their supporting blocks so that they are inoperative on their return stroke. Suitable springs are provided for restoring the dogs to their operative positions before the beginning of the next movement to the right.

It is often necessary to cut a thread up to a shoulder which necessitates the stopping of the die at a fixed point in its travel. For such operation we provide an auxiliary device for shifting the sleeves 66 and 62 through which the high speed gear is controlled. This auxiliary device comprises one or more pins 90 (Fig. 4) slidable in holes in the bearing 21^b and positioned to engage the end of the sleeve 66. The opposite ends of the pins extend beyond the bearing into position for engagement by a collar 91 which may be clamped to the shaft 23 in any desired position. When the collar engages the pins 90 the motion of the shaft 23 will be transmitted directly to the sleeves 66 and 62, and the high speed pawl 61 will thus be forced positively outward at a fixed point in the travel of the shaft 23 and the die 16. While this arrangement is more positive in its action than the compound lever previously described, the latter device is used wherever possible, as the compounding of the levers causes the sleeve 66 to move more rapidly than the shaft 23, and thus throws the pawl into operative position with less opportunity for wear of the parts before driving engagement is established.

A collar 95 loosely encircles the sleeves 66 and 62 and holds the gear 52 in position upon the sleeve 50.

When we desire to remove the threading mechanism or to change it to a different position, we first remove the cross pin 232 (Fig. 4), and the screws 29. The support 21, the sleeve 22 and actuating mechanism therefor, the shaft 23, the sleeves 62 and 66 and the collar 95 may then be removed as a unit. The sleeve 50, cap 50^a, and gears 52 and 53 may then be drawn out of the tool head 15 to the left (Fig. 4) and the spindle 17 and die 16 may be removed to the right. The parts can thereafter be reassembled in a different operating position or they may be laid aside and the usual fixed cutting tools may be substituted therefor.

Having thus described our invention it will be evident that changes and modifications can be made therein by those skilled in the art without departing from the spirit

and scope of our invention as set forth in the claims, and we do not wish to be otherwise limited to the details herein disclosed, but

What we do claim is:

1. In an automatic lathe, in combination, a threading die, driving means effective to rotate said die at each of two different speeds, controlling mechanism for said driving means, devices effective to advance and retract said die axially, actuators for said devices, and means to support said devices, mechanism, and actuators in alinement with either one of two successive operative positions of the work spindle.

2. In an automatic lathe, in combination, a threading die, means to rotate said die at each of two different speeds, a fixed frame member having guide-ways thereon, a removable support slidable on said ways, means to secure said support in fixed position on said ways during the continued operation of the machine, and mechanism mounted on said support through which the thread-cutting operation may be controlled.

3. In an automatic lathe, in combination, a threading die, means to rotate said die at each of two different speeds, a fixed frame member having two sets of guide-ways thereon, a support adapted to be mounted in fixed position on either one of said sets of ways, mechanism mounted on said support through which the thread-cutting operation may be controlled, and means to actuate said mechanism in either position thereof.

4. In an automatic lathe, in combination, a threading die, means to rotate said die at each of two different speeds, a fixed frame member having two sets of guide-ways thereon, a support adapted to be mounted in fixed position on either one of said sets of ways, mechanism mounted on said support through which the operation of the threading die may be controlled, a pair of sliding bars mounted for simultaneous movement on said fixed frame, and a plurality of devices effective when mounted on one of said bars to control the mechanism on said support when on one set of guide-ways, and effective when mounted on the other bar to control said mechanism when supported on the other set of guide-ways.

5. In an automatic lathe, in combination, a threading die, driving means for rotating said die at each of two different speeds, devices connected to move said die axially, and a single actuating member effective to advance and retract said die and to control the speed changes thereof.

6. In an automatic lathe, in combination, a threading die, driving means effective to rotate the die at each of two different speeds, a fixed frame member having guide-ways thereon, a support slidable on said ways, means to secure said support in fixed posi-

- tion on said ways, a rack slideable in said support, a gear pivoted on said support and meshing with said rack, a segment gear on said support connected to turn said first named gear, and actuating means movably mounted on said fixed frame for moving said segment gear in each direction.
7. In an automatic lathe, in combination, a threading die, a spindle through which said die is controlled, means to operate said spindle at each of two different speeds, a fixed frame member having guide-ways thereon, a support slideable on said ways, means to secure said support in fixed position on said ways, a rack slideable in said support, swivel connections from said rack to said spindle, a segment gear connected to slide said rack, a pawl effective to move said gear, rack and spindle in one direction, a second pawl effective to move said parts in the opposite direction, and means to move said pawls.
8. In an automatic lathe, in combination, a threading die, a spindle through which said die is controlled, means to operate said spindle at each of two different speeds, a fixed frame member having guide-ways thereon, a support slideable on said ways, means to secure said support in fixed position on said ways, a rack sleeve slideable in said support, a segment gear connected to slide said sleeve, a bar mounted for positive longitudinal movement, a pawl on said bar effective to move said gear, sleeve and spindle in one direction, a second pawl on said bar effective to move said parts in the opposite direction, and a third pawl on said bar effective to change the speed of rotation of the threading die.
9. In an automatic lathe, in combination, a threading die, a spindle through which said die is controlled, means to operate said spindle at each of two different speeds, a fixed frame member having guide-ways thereon, a support slideable on said ways, means to secure said support in fixed position on said ways, a rack sleeve slideable in said support, a segment gear connected to slide said sleeve, a bar mounted for positive longitudinal movement, a pawl on said bar effective to move said gear and sleeve in one direction, a second pawl on said bar effective to move said gear and sleeve in the opposite direction, and a third pawl on said bar effective to change the speed of rotation of the threading die, all of said pawls being operative during movement of said bar in one direction and being inoperative during the return movement of said bar.
10. In an automatic lathe, a threading die, means to rotate said die in the direction of rotation of the stock at either of two different speeds, mechanism for positioning and controlling said die, a bar slideable parallel to the axis of the die, and a series of
- pawls carried by said bar and effective successively to advance said die, to increase the speed of rotation thereof, and to thereafter return said die to initial position and restore the original speed of rotation all during a single continued travel of the sliding bar in one direction.
11. In an automatic lathe, a threading die, means to rotate said die in the direction of rotation of the stock at either of two different speeds, mechanism for positioning and controlling said die, a bar slideable parallel to the axis of the die, a series of pawls carried by said bar and effective to advance said die, to increase the speed of rotation thereof, and to thereafter return said die to initial position and restore the original speed of rotation all during a single continued travel of the sliding bar in one direction, and cam-actuated means for giving said bar an irregular reciprocating motion.
12. In a threading attachment, a die, a spindle to which said die is secured, low and high speed gears loosely rotatable concentric with said spindle, and pawl and ratchet mechanism by which either one of said gears may be rendered effective to control said spindle and die, said pawls being mounted on a sleeve loosely keyed to the spindle by a tumbler effective to cause positive engagement of the low speed pawl with its ratchet during the cutting of the thread.
13. In a threading attachment, a threading die, a spindle through which the die is controlled, a sleeve on said spindle, low and high speed gears rotatable outside of said sleeve, separate pawls slideable transversely in said sleeve to cause engagement of said gears with said sleeve, external adjustable mechanism for actuating the high speed pawl, and a device for forcing the low speed pawl into driving position yieldingly when running idle and positively when cutting the thread.
14. In a threading attachment, a threading die, a spindle through which the rotation of the die is controlled, a sleeve on said spindle, a low speed gear rotatable concentric with said sleeve and having internal ratchet teeth, a pawl slideable transversely in said sleeve, a spring effective to force said pawl lightly into engagement with said ratchet teeth, and a tumbler loosely confined in a recess in said sleeve and engaging one end of said pawl, said spindle having a keyway therein loosely fitting said tumbler and permitting limited angular movement between said spindle and sleeve, said tumbler acting as a lever when forced ahead by said spindle through engagement with the side of the keyway and being effective to force said pawl positively outward to operatively engage said ratchet teeth.
15. In an automatic lathe, in combination, a threading die, driving means effective to

rotate the die at each of two different speeds, a fixed frame member, a support, means to secure said support in fixed position on said frame, a rack slidable in said support, a 5 gear pivoted on said support and meshing with said rack, a segment gear on said support connected to turn said first named gear, and actuating means movably mounted on said fixed frame for moving said segment 10 gear in each direction.

16. In an automatic lathe, in combination, a threading die, a spindle through which said die is controlled, means to operate said spindle at each of two different speeds, a

rack sleeve connected to said spindle, a segment gear connected to slide said sleeve, a bar mounted for positive longitudinal movement, a pawl on said bar effective to move said gear, sleeve and spindle in one direction, a second pawl on said bar effective to move 20 said parts in the opposite direction, and a third pawl on said bar effective to change the speed of rotation of the threading die.

In testimony whereof we have hereunto set our hands.

JAMES J. HOGAN.
